(57) **CLAIM**

I claim the ornamental design for a multiple EKG display, as shown and described.

DESCRIPTION

FIG. 1 is a perspective view of a multiple EKG display showing my new design;

FIG. 2 is a front view of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1;

FIG. 6 is a top view of the claimed design of FIG. 1;

FIG. 7 is a bottom view of the claimed design of FIG. 1;

FIG. 8 is a detailed front view of the upper left panel of the claimed design of FIG. 1;

FIG. 9 is a detailed front view of the middle left panel of the claimed design of FIG. 1;

FIG. 10 is a detailed front view of the lower left panel of the claimed design of FIG. 1;

FIG. 11 is a detailed front view of the lower central panel of the claimed design of FIG. 1;

FIG. 12 is a detailed front view of the upper right panel of the claimed design of FIG. 1;

FIG. 13 is a detailed front view of the middle right panel of the claimed design of FIG. 1;

FIG. 14 is a detailed front view of the lower right panel of the claimed design of FIG. 1;

FIG. 15 is a detailed front view of the upper central panel of the claimed design of FIG. 1; and,

FIG. 16 is a detailed front view of the middle central panel of the claimed design of FIG. 1.

The broken lines shown in the drawings are for purposes of illustrating environment and portions of the multiple EKG display that form no part of the claimed design.

1 Claim, 14 Drawing Sheets
